CLAIM

The ornamental design for a silicone protective cover as shown and described.

DESCRIPTION

FIG. 1 is a top perspective view of a silicone protective cover, showing my new design;

FIG. 2 is a bottom perspective view thereof;

FIG. 3 is a front elevational view thereof, the rear elevational view being a mirror image of FIG. 3;

FIG. 4 is a left elevational view thereof;

FIG. 5 is a right elevational view thereof; and,

FIG. 6 is a top plan view thereof, the bottom plan view is identical.

The broken lines and unshaded surfaces illustrate portions of the silicone protective cover that form no part of the claimed design.
